UNITED STATES PATENT OFFICE.

MAURICE B. BRAND, OF CHICAGO, ILLINOIS.

MILK-BOTTLE HOLDER.

1,147,368.

Specification of Letters Patent. Patented July 20, 1915.

Application filed June 27, 1914. Serial No. 847,627.

To all whom it may concern:

Be it known that I, MAURICE B. BRAND, citizen of the United States, residing at Chicago, in the county of Cook and State of Illinois, have invented certain new and useful Improvements in Milk-Bottle Holders; and I do hereby declare the following to be a full, clear, and exact description of the invention, such as will enable others skilled in the art to which it appertains to make and use the same.

My invention relates to bottle holders and more particularly to receptacles designed for receiving milk bottles and for protecting them against surreptitious removal before the rightful owner has an opportunity to bring the bottles indoors.

The prime object of my invention is to provide a simple and cheaply manufactured receptacle which may readily be opened by the milkman without the use of a key for removing the empty bottles therefrom and which will automatically lock itself when the cover of the receptacle is closed after the insertion of one or more full milk bottles.

Another object is to provide simple means for guiding a single bottle when inserted in a receptacle of ample size for receiving a number of milk bottles, so as to maintain the said bottle in operative relation to the locking mechanism.

Other objects will be apparent from the following specification and from the accompanying drawings, in which:

Figure —1— is a transverse longitudinal section through a milk bottle holder embodying my invention. Fig. —2— is a longitudinal vertical section through the same. Fig. —3— is a plan view of the same.

In the embodiment of the drawings, the milk bottle holder of my invention comprises a sheet metal casing 1 of substantially oval horizontal section secured to a base 2, which base is shown in the drawings as being of wood. Mounted upon the casing 1 near the upper or normally open end thereof is a pivot 3 forming the connection between the said casing and a cover 4, the said cover being preferably equipped with flanges 5 depending along the sides of the casing 1. Mounted upon the cover 4 is a lock, which lock may be of any suitable type, but preferably including a sliding latch 6, which latch is normally pressed outward by a spring 7. In the drawings, the

lock carried by the cover is shown as of the keyless or combination type more fully disclosed in my copending application filed of even date herewith as Serial No. 857,467. 60 This lock includes an operating knob or handle 8 which may be used both for manipulating the locking disks or tumblers and for raising the cover. The sliding latch member 6 preferably has a pointed tip 9 65 adapted to be slid under the bight or looped portion 10 of a lock member pivotally carried by the casing 1. In the drawings, this locking member is shown as consisting of a wire bent substantially into the form of an inverted U and having its shanks 11 and 12 equipped respectively with transverse or off-set portions 13 and 14, at least one of the said shanks being extended beyond the said off-sets nearly to the lower end of the 70 casing 1. Secured to the said casing near the middle of its height are U-shaped metal members 15 equipped with perforations housing parts of the said transverse portions 13 of the said shanks, whereby the 75 said locking member is rockingly mounted upon the casing. Twisted around the transverse portion 14 and engaging both the adjacent shank 12 and casing 1 is a spring 16, which spring continuously tends to press the 80 upper or bight end 10 of the said movable member against the adjacent side of the casing 1, or into the position shown in dotted lines in Fig. —1—.

The lower end portion or stem 17 of one 90 of the shanks, viz., the shank 12 of Fig. —2—, normally depends at a considerable angle to the adjacent side of the casing 1, the said angle being so proportioned that the said stem 17 will readily clear the 95 mouth end of a bottle 18 when the latter is inserted in the receptacle in an inverted position as shown in Fig. —1—. However, if a bottle is inserted in the holder in upright position, as shown in full lines in Fig. 100 —1—, the lower end thereof (being considerably larger in diameter than the mouth end of the same bottle) will engage the said stem 17 of the movable member while being inserted, and will coöperate with the opposite wall of the casing to move the said member about its pivotal mounting and against the pressure of the spring 16, so as to dispose the said rocking member in the position shown in full lines in Fig. —1—. 110 Consequently, when the cover is thereafter closed, the inclined tip of the hook 9 of the

latched member 6 will force the latched member back somewhat while the cover is being closed, after which the spring 7 will return the member 6 to the position shown 5 in Fig. —1—, thereby causing the hook 9 to engage the bight 10 and to lock the cover against opening. It will be obvious that when the cover is thus locked, the engagement of the lower end of the bottle with 10 the stem 17 of the movable member will continuously hold the bight or loop end of the said member in operative relation to the hook of the latch member. Consequently, if a spring lock is used, the cover cannot be 15 opened until the lock is suitably manipulated to release the said latch, after which the latter may be loosely pressed inward through the aid of a projecting portion 19, so as to release its engagement with the 20 movable member and permit the cover to be opened for withdrawing the bottles from the receptacle.

When the receptacle is to be used for storing more than one bottle, I preferably provide 25 partition members 20 and 21 engaging suitable supports 22 secured to the sides of the casing, which partition members will prevent each bottle from sliding longitudinally of the casing, thereby maintaining the 30 bottle opposite the stem 17 in proper alignment or operative relation to the latter. In the drawings, I have shown the pivot 3 as extending through a portion of the cover affording a hood for the pivot so as to prevent 35 the insertion of a simple tool at the pivot for prying off the cover. However, I do not wish to be limited either to this or other details of the construction herein disclosed, it being evident that the same might be varied 40 in many ways without departing from the spirit of my invention.

I claim as my invention:

1. A bottle holder comprising a receptacle having relatively rigid vertical sides, a movable cover therefor, and means for locking the cover in closing position; said means comprising a latch carried by the cover, a member pivoted upon one of said sides and presenting an upper end portion adapted 45 to be engaged by said latch when said member is in one position, and to clear said latch when said member is in another position; said member also equipped with a lower portion normally depending at an angle to the side to which the member is pivoted, the 50 said angular disposition of the last named portion causing the latter to be disposed in the path of a bottle inserted in the said receptacle, thereby causing the said member 55 to be moved about its pivotal mounting by the insertion of the said bottle in upright position, the angularity of the said disposition of the lower portion of the pivoted 60

member being insufficient to cause said portion to be engaged by the bottle when the latter is inserted in inverted position.

2. In combination with a milk bottle, a holder comprising a receptacle having relatively rigid sides and open at the top, a movable cover for said receptacle, a latching member movably disposed upon the said cover, a movable member pivotally mounted within the receptacle and presenting an arm disposed in the path of the bottle when the latter is inserted in the receptacle in upright position and equipped with a horizontal portion normally out of engagement with the said latch, the said horizontal portion of the movable member adapted to be moved into engagement with the said latching member when the said arm is moved out of its normal position; spring means associated with the receptacle and the said movable member for holding the latter in its normal position, and guide means for 85 guiding the bottle in a direction transverse to the direction of movement of the said arm of the movable member, the said guide means coacting with wall portions of the receptacle to maintain the bottle in operative relation to the said movable member when the said bottle is inserted in the receptacle in an upright position.

3. A bottle holder including a casing having relatively rigid sides, a cover hinged thereto, a movable latch carried by the cover, and a rocking member carried by the casing and coöperating with the latch to lock the cover; said member comprising a bight disposed adjacent to said latch, and a pair of shanks depending from said bight and each equipped with an off-set, at least one of said shanks having a stem extending beyond the off-set in the same approximately to the lower end of the casing; bearings carried by the casing and housing parts of the said off-set portions to afford a pivotal support for the said rocking member, and a spring associated with the rocking member and the casing and normally holding the rocking member with the bight thereof out of coöperating relation to the said latch; the said stem of the rocking member normally depending at an angle to the adjacent side of the case, said depending portion being outside the path of an inverted bottle inserted in the casing but within the path of an upright bottle inserted therein.

In testimony whereof I have signed my 120 name in presence of two subscribing witnesses.

MAURICE B. BRAND.
